US00D932927S

(12) **United States Design Patent** (10) **Patent No.:** **US D932,927 S**
Wu et al. (45) **Date of Patent:** **** Oct. 12, 2021**

(54) **BARBECUE THERMOMETER**

(71) Applicant: **Shenzhen Intellirocks Tech. Co., Ltd.**,
Shenzhen (CN)

(72) Inventors: **Xiaoting Wu**, Shenzhen (CN);
Wenlong Wu, Shenzhen (CN)

(73) Assignee: **Shenzhen Intellirocks Tech. Co., Ltd.**,
Shenzhen (CN)

(**) Term: **15 Years**

(21) Appl. No.: **29/759,359**

(22) Filed: **Nov. 23, 2020**

(51) **LOC (13) Cl.** **10-04**

(52) **U.S. Cl.**

USPC **D10/57**

CLAIM

The ornamental design for a barbecue thermometer, as shown and described.

DESCRIPTION

FIG. 1 is a front view of a barbecue thermometer, showing our new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a front perspective view thereof; and,

FIG. 8 is a back perspective thereof.

The broken line showing of the barbecue thermometer is for the purpose of illustrating unclaimed portions of the barbecue thermometer and forms no part of the claimed design.

1 Claim, 8 Drawing Sheets
